UNITED STATES PATENT OFFICE.

NEWMAN R. MARSHMAN, OF NEW YORK, N. Y.

TOY THEATER OR PUNCH-AND-JUDY SHOW.

SPECIFICATION forming part of Letters Patent No. 256,909, dated April 25, 1882.

Application filed January 11, 1882. (No model.)

To all whom it may concern:

Be it known that I, NEWMAN R. MARSHMAN, a citizen of the United States, residing at the city, county, and State of New York, have invented certain new and useful Improvements in Toy Theaters or Punch-and-Judy Shows, of which the following is a specification.

This invention relates to that class of mechanical toys in which figures are made to move on a stage or platform.

The novel features of the invention pertain to certain mechanical devices by which transformations are effected and the figures made to move, appear, and disappear automatically by the rotation of a crank or shaft, the object being to impart to the figures a life-like appearance by means that are simple and not liable to disarrangement.

Before describing my invention I wish to say that I do not limit myself to any particular scenic representation, nor to any particular number of figures or transformation effects. For convenience I have shown only enough of such effects and figures to illustrate my invention and a stage of very limited dimensions. My object is to illustrate most particularly the mechanical constructions.

In the drawings, Figure 1 is a front view of the figures and their actuating mechanism disengaged of the surrounding casing. Fig. 2 is a front elevation of a stage on which the figures move. Fig. 3 is a sectional elevation on line 3 3 in Fig. 1, and Fig. 3^a is a small detached plan view, which will be explained hereinafter. Fig. 4 is a sectional elevation on line 4 4 in Fig. 1. Fig. 5 is a sectional elevation on line 5 5 in Fig. 1. Fig. 6 is a sectional elevation on line 6 6 in Fig. 1. Fig. 7 is a sectional elevation on line 7 7 in Fig. 1. Fig. 8 is a modification, which will be referred to hereinafter. Figs. 3, 3^a, 4, 5, 6, 7, and 8 are drawn to a smaller scale than Figs. 1 and 2. In all the sectional elevations the view is taken from the right in Fig. 1, looking toward the left.

Let A represent in general the housing around the stage, and B the floor or stage proper. C is a roller, which may be turned from wood. This roller has raised flanges *a b c d* and a broader flange or drum, *e*, to serve

as a driver for an endless belt or apron, D. 50 The roller has also journals *g g*, whereon it is rotatively mounted in the housing A, and one of these journals projects and bears an operating-crank, *g'*.

The figures E and F are made to move in 55 the same way and by the same kind of mechanism; but not necessarily to be actuated simultaneously, so it will only be necessary to describe the mechanism for actuating one, as E. By referring to Figs. 1 and 3 it will be 60 seen that this figure is mounted on a block, *h*, which is pivoted in the stage-floor B just behind a door-opening in the scene A'. A portion of the block *h* is arranged to rest on and be supported by the flange *a* on the roller C; 65 but a portion of this flange is cut away, as at *i*, and as the roller C is turned (see arrow in Fig. 3) the block drops into the recess *i* and permits the figure E to fall prone on its face and out of sight, as in the full lines in Fig. 3. 70 As the rotation continues the margin of the recess *i* catches on the block *h* and again throws the figure up, giving it the appearance of suddenly appearing and disappearing at the door in the scene. The figure F operates in the 75 same way, except that one figure is made, or may be made, to appear as the other disappears, as if dodging each other. E is designed to represent a policeman, and F to represent Punch. The heads of the figures E and F are 80 fixed on stems which pass down through the bodies and out below, and on the lower ends of these are fixed star-wheels *a'*, as shown detached in Fig. 3^a. When the roller C is re- 85 volved the points on these wheels catch against pins *b'* in the roller and turn the heads of the figures.

If it be desired to cause the head to turn from side to side, the pins *b'* are arranged in two rows in alternate order, as shown in Fig. 90 1; but if it be desired to turn the head entirely around the pins must be arranged uniformly in one row, so as to engage but one side of the wheel *a'*.

The figures are shown as arranged to fall 95 forward on their faces through an opening in the stage-floor; but by reversing the rotation of the roll C they may be made to fall back.

The endless belt D passes over an idler-pulley, e, arranged near the front or foot-lights of the stage, and on this are pivotally mounted any number of figures, G, H, and I. The figures 5 are weighted below, as at j, and are pivoted in uprights k, secured to the belt D. The figures move along in a natural manner toward the front of the stage (the uprights k and weights j being practically out of sight) and 10 pass down through the stage at the front, feet foremost, as shown in Fig. 5. A number of figures may be made to follow each other in this way, as in a procession coming through a door, l, in the scene A', hung to close elastically, so as to be opened by the pressure of 15 the figure against it.

The figures G, H, and I represent respectively a policeman, Punch, and Judy.

J is a head mounted on the free end of a lever, m, one end of which is pivoted at the back part of the stage behind the scenes. The end of the lever bearing the head J rests on a cam formed out of the flange c. When the roller C turns, the cam e raises the head J slowly 25 through a hole or trap in the stage-floor, and then allows it to drop suddenly. The head is fixed on a stem, n, Fig. 1, which is pivoted at its middle to the lever m or to a block thereon, and the lower free end of the stem is acted 30 upon, when the head is raised, by pins or projections o on the side of the cam, which causes the head to move slightly from side to side. The object of this is to impart a slight movement to give a life-like appearance to the figure. 35 In Figs. 1 and 7 is illustrated the mechanism employed for raising the curtain K at the front of the stage. This curtain is arranged to roll up on a properly-mounted roller, p, and may be weighted at its lower edge, so as to unroll 40 of itself.

On the end of the roller is wound a cord, q, which passes back over an idler-pulley, r, and thence to the long arm of a lever, s, pivoted just over the roller C. In the flange d on said 45 roller is formed a recess, t, the margin of which, when the roller is turned, catches against the short arm s' of the lever and throws the lever down, thus unwinding the cord q and rolling up the curtain. The curtain remains rolled up 50 until the short arm s' again drops into the recess t, as will be well understood. Fig. 7 shows the curtain being wound up.

In Figs. 1 and 4 I have shown a device for exhibiting a legend to indicate what the figures 55 on the stage are supposed to be saying. This consists simply of an endless belt, u, on which the legends are inscribed or printed, arranged to pass over a portion, f, of the roller C and to be driven thereby. The belt passes forward 60 and over rollers or rods v v in such a manner as to display the legends successively at an opening, w, at the front and below the stage by preference.

In Fig. 2 I have shown the legend "Now 65 I've got you," which is supposed to be spoken

by policeman E. The length of belt, &c., must of course be arranged to exhibit the legends at the proper time; but this may be arranged by any one.

In lieu of displaying a legend in front for 70 the benefit of the audience, it may be displayed at the back to prompt or guide the exhibitor, who may wish to speak the legends aloud from behind the stage.

In Fig. 8 I have shown mechanism for causing a figure—say E—to nod instead of turn the head sidewise. This is accomplished by hinging the head to the body in front, as at x, and extending a rod or tracker-pin up through the body to take under the back part of the 80 head. The lower end of this rod rests on and is supported by a leaf-spring or hinged plate, y. As the roller C revolves, pins b' on the roller take under said plate y successively and lift and drop it and the tracker-pin, thus giving 85 the head a nodding motion. This mechanism may be substituted for that shown in Figs. 1, 3, and 3^a.

Having thus described my invention, I claim—

1. In a toy, the combination, with a revolving roller having a recess and shoulder, of a figure pivoted over said roller on a block and arranged to be thrown up to an erect position by the engagement of the shoulder with said 95 block, substantially as set forth.

2. In a toy, the combination, with a roller provided with a recessed flange, a, and pins b', of a figure, E, mounted on a block, h, pivoted over the roller, the head of the figure being 100 arranged to be moved independently by means of a stem acted upon by the pins b' in the roller as the latter turns, all arranged substantially as and for the purposes set forth.

3. The combination, in a toy, of a roller, an 105 endless band or apron, an idler-pulley for the band to pass over, and a figure or figures pivotally mounted on said band and weighted at the bottom to maintain them in an erect position, substantially as and for the purpose set 110 forth.

4. In a toy, the combination, with a figure arranged to be thrown up to an erect position by means of a shoulder on a roller, and the said shouldered roller provided with projecting pins, of a star-wheel, a', fixed on the lower end of the stem which bears the head of the figure, substantially as set forth.

5. In a toy theater wherein figures appear and move on the stage, the combination, with 120 the roller which actuates the figures, of a belt or apron bearing legends or inscriptions, the said roller and apron being arranged to exhibit said inscriptions at the proper times in order to illustrate the acts or purposes of the 125 figures on the stage, substantially as set forth.

6. The combination, in a toy, of an actuating roller, C, provided with a cam, e, a head, J, a stem, n, a lever, m, on which the head is pivoted, and projections o on the sides of the cam e, said 130

projections being arranged to impinge against the stem *n* as the cam rotates and raises the head into view, substantially as set forth.

7. In a toy theater wherein a stage is employed, the combination, with an actuating-roller, *C*, for imparting movements to the actors or figures, of a curtain, *K*, curtain-roller *p*, cord *q*, lever *s*, provided with a short arm, *s'*, and a notched flange, *d*, on the roller *C*, arranged

to actuate the lever *s* and raise the curtain, to substantially as set forth.

In witness whereof I have hereunto signed my name in the presence of two subscribing witnesses.

NEWMAN R. MARSHMAN.
